UNITED STATES PATENT OFFICE.

MORRIS WOLOCK, OF CHICAGO, ILLINOIS.

DESIGN FOR A SHOE BOX.

Application filed May 18, 1928. Serial No. 26,742. Term of patent 7 years.

To all whom it may concern.:

Be it known that I, MORRIS WOLOCK, a citizen of the United States, residing at Chicago, in the county of Cook and State of Illinois, have invented a new, original, and ornamental Design for Shoe Boxes, of which the following is a specification, reference being had to accompanying drawing, forming part thereof.

The figure is a perspective view of a shoe box, showing my new design.

I claim:

An ornamental design for a shoe box, as shown.

In testimony whereof I affix my signature.

MORRIS WOLOCK.
